GEORGE M. PAGE, OF HAYDENVILLE, MASSACHUSETTS, ASSIGNOR TO THE HAYDENVILLE COMPANY, OF HAYDENVILLE, MASSACHUSETTS, A CORPORATION OF NEW JERSEY.

DRINKING-FOUNTAIN NOZZLE.

1,158,147.

Specification of Letters Patent.

Patented Oct. 26, 1915.

Continuation of application Serial No. 790,637, filed September 19, 1913. This application filed November 28, 1914. Serial No. 874,417.

To all whom it may concern:

Be it known that I, GEORGE M. PAGE, a citizen of the United States of America, and a resident of Haydenville, in the county of 5 Hampshire and State of Massachusetts, have invented a new and useful Drinking-Fountain Nozzle, of which the following is a specification.

My invention relates to improvements in 10 nozzles for drinking fountains, and consists of a peculiarly chambered and perforated device that is capable of being mounted over the open or discharge end of a supply pipe, all as hereinafter set forth.

15 The objects of my invention are, first, to produce a device of the kind specified above which is very simple in construction and operation, can be readily applied to almost any supply pipe, consisting as it does of practically a single element, is comparatively inexpensive to manufacture, and is quite safe for use for young children as well as adults; 20 second, to produce such a device that is capable under normal conditions of delivering water in bubbles which are projected well 25 above the place of exit, as is best for drinking purposes, while being incapable even under abnormal conditions of squirting, and which is entirely sanitary; third, to produce 30 a drinking-fountain nozzle so constructed that the water passing through the same is aerated and thus purified, made more lively, and caused to sparkle, and, fourth, to produce 35 a nozzle which in itself is a drinking fountain.

Other objects will appear in the course of the following description.

I attain these objects by the means illustrated in the accompanying drawings, in 40 which—

Figure 1 is a top plan of a practical and preferred form of my nozzle; Fig. 2, a side elevation of said nozzle, showing it mounted on a supply pipe; Fig. 3, a central vertical 45 section through the parts shown in the preceding view; Fig. 4, a bottom plan of the nozzle; Fig. 5, a fragmentary section showing a slight modification, and, Fig. 6, a similar section showing still another slight modification.

Similar numerals refer to similar parts throughout the several views.

The nozzle herein illustrated is a shell-like structure which comprises a tubular stem 1

that terminates on the inside at the top in a 55 dome 2 having one or more perforations 3 in the sides thereof, that is, lateral perforations; an intermediate chamber 4 into which said dome extends and opens through said perforations, the walls of such chamber rising first from said stem and then being caused to converge to form a top opening 5, and such walls having one or more perforations 6 therein, which may be located at or near the bottom of said chamber in such a 65 manner that they open outside of said stem, as shown in Fig. 3; and an upper chamber 7 formed by the outer walls of the shell and surrounding the upper part of the walls of said chamber 4, there being one or more 70 openings 8 in the bottom of said chamber 7 which overhangs the parts below, one or more openings 9 in the top of said last-mentioned chamber, and a central opening 10 in said top just above the horizontal plane of 75 the opening 5 or of the upper end of the walls of the chamber 4. The opening 10 is of larger diameter than the opening 5. The upper portion of the walls of the chamber 4 forms what may be termed an interior or inferior nozzle or a throat piece 11. That part of the shell of the nozzle in which the chamber 7 is located may be termed a head 13, and this head has a concave top or mouth-piece 14 in which are the openings 9 and 10. 80 An annular channel 15 is formed in the overhanging bottom part of the head 13 and the openings 8 lead from such channel upwardly to the chamber 7.

When water under pressure enters the 90 dome 2, through the stem 1, it impinges against the closed top of said dome and is forced out through the perforations 3 into the chamber 4, and then passes upward around the outside of said dome, is constricted by the throat piece 11 or the walls of 95 said chamber, and finally escapes through the openings 5 and 10. Thus the column of water is greatly constricted and broken up at the start, then permitted more freedom 100 upon its escape from the dome 2 into the chamber 4, and lastly is again constricted, although less than the first time and without being broken into spray or small streams. The water rises from the opening 10 ready 105 for drinking, being presented in the most palatable as well as most convenient form. Under proper conditions the stream or col-

umn of water is projected some distance above the top 14, mushrooming as the water continues to rise, until gravity overcomes the force behind the water and the latter falls in and around the top of the head 13. 5 Most of the water falls beyond or flows over the rim of the head 13, but so much thereof as does not escape from the top 14 through the openings 9 into the chamber 7 and from 10 there through the openings 8 and the groove 15 to the space below said head. As a matter of fact, comparatively little water passes into the chamber 7.

The exterior overhang of the parts which 15 form the channel 15, such overhang being represented at 16, affords a water-shed or guide for the overflow or waste water, which is thereby kept away from the openings 8 and permitted to flow off freely.

20 If an attempt be made to cause the nozzle to squirt, by partially covering the opening 5, such attempt will fail, because the water thus obstructed and that would naturally escape with great force through said opening, 25 under conditions tending to produce a squirt, instead passes downwardly through the openings 6 and does no harm. The same thing happens in case the opening 5 be closed entirely. Then, again, relief from excessive pressure that might be occasioned by 30 partially or wholly covering the opening 10, or said opening together with the openings 9, is relieved or prevented by the presence of the openings 8, the water then flowing 35 out at the top of the chamber 4 into the chamber 7 and then passing down and out of said chamber 7 through said openings 8. Thus it is clear that all possibility of improper use of the nozzle is obviated, and 40 that the latter is especially well adapted for use by children, since there is no liability that they will get wet by the indulgence of some in the common practice of attempting to squirt the water by covering or constricting the nozzle at the normal point of discharge. 45 With most devices of this character it is possible to reduce the stream, by partially closing the exit opening, and to throw or squirt the water with considerable 50 force in various directions, while with my device the water, when held back at the normal point of discharge is relieved of excessive pressure at such point, and being so relieved can not be manipulated for squirting purposes, but simply finds its escape in 55 other directions and through other exits without material increase in velocity.

The concave top or mouth-piece 14, with its rounded edges, is quite an important 60 factor in the invention, on account of the bearing surface thus provided and presented for the mouth. This bearing surface is especially well adapted for the reception of the lower front portion of the face, while 65 a person is in the act of drinking, and with

it there is no liability of such person being injured by contacting therewith. The upper jaw just under the nose and the chin are the parts of the face that can contact at all forcibly with the top or mouth-piece 14, so that 70 the lips are left free for drinking, and there is little or no danger of injury to the teeth in the event the head be forcibly thrust against such mouth-piece.

The nozzle is self-draining, that is to say, 75 when the water is shut off the nozzle clears itself, the water in the chamber 4 escaping through the openings 6 and the waste water through the openings 9, 10, and 8.

In Figs. 2 and 3 the nozzle is represented 80 as mounted on a fragment of a supply pipe 17, the interior of the stem 1 being screw-threaded for that purpose. The stem might equally well be externally screw-threaded and attached to the inside of the supply 85 pipe.

In most cases means must be provided for cutting down and regulating the normal water pressure in the supply pipe before the water reaches the discharge openings 5 and 90 10, for reasons which will be well understood, and one such means I have shown in Fig. 3, but I am aware that there are many other devices which would serve the same purpose. The regulator in this case is really 95 a reducer, that is to say, it is a device for cutting down the volume, so that, although the velocity is thereby initially increased, such velocity is subsequently reduced to the amount necessary as the water flows through 100 the nozzle, owing, of course, to the reduction in volume. The reducer above referred to consists merely of a tapering seat 18 in the upper terminal portion of the supply pipe 17, and a regulating screw 19, with which 105 latter may be used a check-screw 20. The screw 19 is tapered at the base to correspond with the taper of the seat 18, and the check-screw 20 by preference also has a tapered base. Both screws have grooves or waterways 21 in their sides. The interior of the pipe 17 above the seat 18 is screw-threaded 110 to receive the two screws.

In practice, while the check-screw 20 is 115 out of the pipe 17, the regulating screw 19 is turned up or down to produce the right amount of space between the seat 18 and the base of said regulating screw, and then said check-screw is replaced in said pipe and turned down tightly on the head of said 120 screw 19 to prevent the latter screw from getting loose and out of its correct place of adjustment. After the reducer has thus been set, the water which passes upward through the seat 18 and the waterways 20 is cut down in volume, so that the velocity of 125 such stream can be and is reduced the required amount as the water flows through the nozzle.

As previously intimated, I do not desire 130

or intend to be restricted to any particular means for controlling the volume of water admitted to my nozzle. It is to be observed, furthermore, that more or less change in the 5 shape and size of said nozzle, and in the arrangement, size and proportions of the perforations and openings therein, may be made without departing from the nature of my invention. In connection with the above 10 reservation attention is called to Figs. 5 and 6. In the first of these two views the openings 6 are omitted from the bottom of the chamber 4, and the walls of said chamber have lateral perforations or openings 12 15 therein; while in the last view both sets of openings 6 and 12 are present.

No means is shown for letting on and shutting off the water, in connection with this nozzle, since it is obvious that a suitable 20 valve for this purpose must be provided at some convenient point. It is immaterial whether the water runs constantly through the nozzle, or be admitted thereto intermittently and only as desired for immediate 25 use. It may be observed, however, that the nozzle is particularly well adapted for use in cases where the water is left running, because, owing to its peculiar construction, satisfactory service is rendered by said nozzle 30 when a comparatively small quantity of water is supplied thereto; thus the waste of water when allowed to flow continuously is kept down to the minimum.

What I claim as my invention, and desire 35 to secure by Letters Patent, is—

1. A drinking fountain nozzle comprising a shell having an inner chamber and an outer chamber therein, the former extending into the latter and having an opening 40 through the top and another opening below such top, and said outer chamber having a concave top and one or more air openings in the bottom and a central discharge opening in said top above the top inner-chamber 45 opening, and a dome extending into said inner chamber and opening laterally through the sides thereof into said last-mentioned chamber, said dome communicating with the inlet end of the nozzle.

2. A drinking fountain nozzle comprising a shell having an inner chamber and an outer chamber therein, the former extending into the latter and having an opening through the top and another opening below 55 such top, and said outer chamber hav-

ing top and bottom openings and a central opening above the top inner-chamber opening, the top of said outer chamber being concave, and a dome extending into said inner chamber and opening laterally through the sides thereof into said last-mentioned chamber, said dome communicating with the inlet end of the nozzle. 60

3. A drinking fountain nozzle comprising a tubular stem terminating at the top, inside, in a dome which is perforated laterally, a chamber surrounding the upper part of said dome, said chamber having walls which are constricted above said dome, are open at the top, and are perforated below 70 such top, and a head surrounding and overhanging said walls, said head having a concave top and a chamber into which said walls extend, and opening through the bottom and through said top above the opening 75 at the top of said walls.

4. A drinking fountain nozzle comprising a tubular stem terminating at the top, inside, in a dome which is laterally perforated, walls surrounding the upper part of said dome and constricted above said dome to form a throat piece, said walls being perforated, and a hollow head surrounding said walls and throat piece and provided with an exteriorly concave top which opens above 80 said throat piece and at one or more points outside of the opening above the throat piece, said head also opening at the bottom outside of the nozzle. 85

5. A drinking fountain nozzle comprising 90 a tubular stem terminating at the top, inside, in a dome which is perforated laterally, walls surrounding the upper part of said dome and constricted above the latter to form a throat piece, said walls being perforated, and a hollow head surrounding said walls and throat piece, provided with an exteriorly concave top which opens above 95 said throat-piece and at one or more points outside of the opening above the throat piece, 100 and overhanging the parts of the nozzle below, the overhanging part of such head having an annular groove in its underside, and the chamber in said head opening through the bottom into such groove.
